UNITED STATES PATENT OFFICE

156,794

ASH TRAY

Harvey R. Wingo, San Diego, Calif.

Application March 27, 1947, Serial No. 137,976

Term of patent 14 years

(Cl. D85—2)

To all whom it may concern:

Be it known that I, Harvey R. Wingo, a citizen of the United States, residing at San Diego, in the county of San Diego and State of California, have invented a new, original, and ornamental Design for an Ash Tray, of which the following is a specification, reference being had to the accompanying drawing, forming part thereof, in which—

Fig. 1 is a plan view of an ash tray, showing my new design;

Fig. 2 is a side elevation of the tray shown in Fig. 1, and

Fig. 3 is a cross-sectional view thereof.

I claim:

The ornamental design for an ash tray, as shown.

HARVEY R. WINGO.
